APPARATUS FOR EXTRUDING METALS

Conrad C. Jacobson, Glen Ridge, N. J., assignor to
John Robertson Co., Inc., Brooklyn, N. Y., a
corporation of New York

Application February 16, 1934, Serial No. 711,466

6 Claims. (Cl. 22—79)

The present invention relates to the method of, and apparatus for extruding metals, and more particularly to the melting of lead and lead alloys and in the charging of the molten metal free from 5 oxides and oxidizing influences to a lead cable press or the like, and constitutes certain improvements over the invention disclosed in my co-pending application, Serial No. 626,442, filed July 30, 1932. In said aforementioned application I 10 have disclosed a method and apparatus for melting lead in an atmosphere of an inert or non-oxidizing gas such as carbon dioxide, and means for introducing such gas into the lead delivery tube and into the extrusion cylinder of the press, 15 so that when said cylinder is being charged with molten lead, said lead will flow through and into the gas-charged space out of contact with the air and thereby practically preclude and reduce to a minimum the formation of objectionable 20 lead oxides.

According to my present invention I further guard against contact of the air with the molten lead being charged to the press, and also provide an improved means for insuring against foreign 25 matter which may find its way into the molten metal in the melting kettle from being charged to the press. A further feature of novelty resides in the swinging connection between the discharge chute for the molten metal and the delivery tube 30 leading from the melting kettle. My invention also embodies other features of novelty which will be hereinafter more fully described.

A preferred embodiment of my invention is illustrated in the accompanying drawings, wherein: 35 Figure 1 is a diametrical section of an apparatus embodying my invention.

Fig. 2 is a top plan view of the device shown in Fig. 1.

Figs. 3 and 4 are fractional enlarged sections 40 showing certain features of the invention.

Figs. 5 and 6 show a bottom plan view and a side elevation, respectively, of another detail of the invention.

Referring to the drawings, let A indicate an 45 extrusion cylinder of a cable covering press or the like, and B the reciprocating ram which is movable within the cylinder A, it being obvious that the specific construction of the cable press may be such as desired.

Disposed in close proximity to the cylinder A is 50 a lead melting pot or kettle C suitably mounted above a fire box D within a furnace housing E which is suitably lined with fire brick e and heat-insulating brick 2e, the furnace being suit-

ably fired through a firing hole (not shown) and having a suitable vent opening 3e near its top.

The melting pot or kettle C is preferably constructed of welded steel plates and is equipped with a draw-off tube c which extends through the wall of the kettle somewhat above the bottom thereof and is of a length to extend inwardly into the kettle to a point near the axis thereof, so that in drawing off molten metal from the kettle, said molten metal will be drawn from approximately the center of the kettle, thereby reducing the probability of drawing off dross or foreign matter which may have accumulated at the side walls of the kettle. The draw-off tube c is preferably welded into the wall of the melting pot and 15 extends outwardly therefrom to a point within the encircling wall of the furnace E which is provided with an opening 4e through which extends the end of a delivery tube F having an offset portion f which extends outwardly and down- 20 wardly through the opening 4e. The draw-off tube c is secured to the delivery tube by screw threads or other equivalent means. Suitably supported by the delivery tube F is the draw-off control valve G which is mounted at one end of a valve stem g which screw-threadedly engages within a bushing 2g and slidably passes through a packed gland 3g. At the outer end of the valve stem g is a hand wheel 4g for controlling the valve. Disposed on the outer 30 side of the wall E around the opening 4e and enclosing the delivery tube F and draw-off valve G is a guard plate H which serves to protect an operator from the heat and flame within the fire box and which extends up around the kettle C, the 35 draw-off tube c, and the delivery tube F. Extending into the delivery tube F, preferably at a point near its top, is a tube 2f having a spring-pressed valve 3f therein through which the admission of a non-oxidizing gas to the delivery tube is controlled. Preferably such non-oxidizing gas is pre-heated by passing through a coiled tube 5e disposed within the furnace wall.

The kettle C is suitably supported in depending relation to the top wall of the furnace by a supporting ring or flange 2c, which may be suitably secured to the kettle by braces 3c. Disposed within the melting kettle C in eccentric relation thereto and supported in depending relation from the top of the said kettle is a melting chamber J, 50 which, at its bottom, is formed with openings j providing for communication between the interior of the melting chamber and the interior of the melting kettle. Extending outwardly from the top of the kettle is a cylinder extension portion 4c!

provided with a cover element 5c having an opening 6c therein through which a non-oxidizing gas such as carbon dioxide may be supplied to the interior of the kettle. Such gas may be obtained from any suitable reservoir such as a tank K, through suitable connections and valves (not shown).

The construction thus far described is substantially the same as that disclosed in my aforesaid application, Serial No. 626,442, and the parts hereinafter described are primarily directed to the novel features of the present invention.

Extending into the melting chamber J in relatively close spaced relation to the side and bottom walls thereof, is a removable liner element L which is dependably supported from the top of the melting chamber J by an annular flange I. This liner element may be made of steel or other suitable material and has near its bottom a plurality of openings 21 for establishing communication between the interior of the liner and the interior of the melting chamber. The lead or other metal which is to be melted in the kettle C may be charged by any suitable means into the liner L, wherein it is melted by the heat communicated to it through the melting kettle C and melting chamber J. As the metal which is usually charged into the melting kettle contains impurities which provide a dross which floats on the surface of the molten metal, as does also the lead oxides formed within the kettle due to exposure and contact with the atmosphere, the liner L serves to facilitate the removal of this dross and objectionable oxides from the molten metal prior to said objectionable substances finding their way into the melting kettle C. To accomplish this the liner L is raised out of the melting chamber J, in the course of which action the molten metal will progressively flow through the openings 21 into the chamber J, whereupon, as the bottom of the liner reaches a point corresponding to the upper surface of the metal in the chamber J, all the dross and foreign matter will be trapped on the bottom of the liner L and can be readily discharged therefrom by the complete removal of the liner from the chamber J. This process of removal of the objectionable foreign substances from the molten metal, it will be appreciated, can be accomplished without shutting down the furnace or exposing the mass of the molten metal therein to the action of the oxidizing influences of the atmosphere, and accordingly provides a distinct improvement over prior constructions.

To prevent the oxidation of the molten metal as it is being flowed from the melting kettle to the extrusion cylinder of the press, I provide a novel form of spout and spout-carrying member M which has an upright part m formed at its top with an internal spherical seat 2m adapted to engage the complementary, spherical seat 4f at the lower end of the delivery tube F. To hold said seating surfaces in leak-tight engagement while at the same time provide for relative circumferential movement therebetween, the member M is pressed upwardly to provide such leak-tight engagement by a pair of springs 2m' carried in adjustable compressible relation upon screw-threaded pins 3m depending from a bracket member 4m secured to the wall of the furnace E, the said springs pressing upwardly against a yoke 5m slidably mounted upon the pins 3m, said yoke carrying on its upper face centrally thereof a stud 6m carrying a roller bearing which

engages in an axial recess in the lower end of the part m. The spout-carrying member M adjacent its top is formed with an offset portion 1m having a central passage 8m therethrough, which, at its spout-supporting end, terminates in a plurality of concentric bores of increasing diameters 8m and 10m. Mounted within the bore 8m is a bushing 11m which carries the discharge spout tube N, said bushing having a flange engaging the wall of the bore 10m, there being holes 11m' extending longitudinally through the bushing. Preferably the interior diameter of the tube N and that of the bushing 11m should be the same as that of the bore 8m at the point of union therewith so as to provide a smooth passage for the molten metal. Slidably fitted between the outer wall of the bushing 11m and the bore 10m is the end of a tube O. At the innermost end of the bore 10m, whereat the bushing 11m provides therewith an annular recess, there extends through the parts 20 1m a pipe or fitting 12m, which connects with a flexible hose 13m, and through said hose with a pipe 14m leading to the source of non-oxidizing gas, the admission of which gas to said pipe 14m is controlled by a valve 15m. The tube O at its 25 opposite end engages within a shouldered bore in a fitting or member P having an axial opening through which the discharge spout tube N extends, leaving a gas passage between said tube and fitting. The fitting P is held in assembled relation to the tube O through the medium of a pair of tie-bolts p. Also disposed in aligned openings in the part 1m and P, and preferably below the tube O, is a gas burner tube R adapted to be supplied with gas through a tube r, said burner being intended for maintaining the discharge spout tube at a temperature to prevent chilling of the molten metal. Enclosing the space provided between the parts 1m and P and for confining the heat of the flame from the 40 burner R, I provide a casing S, which, at its top, is preferably formed with an opening s for venting the products of combustion from the burner flame. Secured to the outer end of the fitting P in encompassing spaced relation to the end of the 45 tube N, is a bent tube or elbow T. For preventing chilling of the molten metal at the discharge end of the spout, I provide a pair of gas burner jets U adapted to direct flames around said end. Gas is supplied to said burners through a tube 27. For manipulating the discharge spout into and out of filling relation to the extrusion cylinder, the part P is provided with an operating handle 2p.

In the operation of my apparatus it will be apparent that when it is desired to charge the cylinder A with oxide-free lead or the like metal, that such can be accomplished in the following manner: The discharge end of the spout is brought into position directly over the mouth of the cylinder A when the ram B is in withdrawn position. The valve 3f is then opened to permit a charge of preheated non-oxidizing gas to expel all the air from the delivery tube F, the spout tube N and the chamber A. The valve 3f is then closed and the valve 15m opened to provide a cylindrical wall of non-oxidizing gas around the discharge end of the tube N. The lead valve G is then opened, whereupon the molten lead will pass down through the delivery tube F, discharge spout tube N and into the cylinder A, it being apparent that as said lead leaves the discharge spout tube N it is encased or shielded by a wall of non-oxidizing gas issuing from the tube T which effec- 75

tively protects the lead against oxidation. When the cylinder A is filled, the valves G and 15m are closed, the charging spout is manually moved to one side about its swing joints 2m, 4f, and m, 6m, and the ram B is then moved downwardly into the cylinder for extruding the charged metal therefrom.

It will thus be seen that according to my present invention I provide a method of and means for efficiently charging lead or like metals free from objectionable oxides or other impurities to an extrusion cylinder of a lead cable press or the like, and thereby practically eliminate failures in lead sheathings for cables due to the presence of lead oxides therein.

While I have shown and described a preferred embodiment of my invention, it is to be understood that I do not wish to be limited to the details of construction disclosed, since the same may be varied within the range of engineering skill without departing from the spirit of my invention.

What I claim is:

1. A device of the character described, comprising a source of molten metal, a source of non-oxidizing gas and a delivery chute having at its discharge end a spaced encircling sleeve providing a discharge nozzle for the chute with concentric bores, said chute having connections with both the source of molten metal and the source of non-oxidizing gas, said latter connection being such that gas may be supplied and discharged from either of the concentric bores of the nozzle.

2. A device of the character described, comprising a source of molten metal, a source of non-oxidizing gas and a delivery chute having at its discharge end a spaced encircling sleeve providing a discharge nozzle for the chute with concentric bores, said chute having connections with both the source of molten metal and the source of non-oxidizing gas, one of said connections establishing communication between the source of molten metal and the inner bore of the nozzle, and another of said connections establishing communica-

cation between the source of non-oxidizing gas and the outer concentric bore of the nozzle whereby both molten metal and gas may be simultaneously discharged from the nozzle with the gas in surrounding relation to the molten metal.

3. A device of the character described, comprising a source of molten metal and a delivery chute leading therefrom having at its discharge end a downwardly-extending branch and an encircling tube connected with a source of gas, said downwardly-extending branch and said encircling tube constituting a discharge nozzle through which molten metal and a wall of gas enclosing the molten metal can be simultaneously discharged from the chute.

4. A device of the character described, comprising a kettle for melting lead and like metals having a separate melting chamber extending into the kettle through the top thereof, means providing communication between the melting chamber and the kettle, and means within said melting chamber for preventing oxides and other foreign bodies from gaining access to the melting chamber proper.

5. A device of the character described, comprising a kettle for melting lead and like metals having a separate melting chamber extending into the kettle through the top thereof, means providing communication between the melting chamber and the kettle, and a removable chamber in said melting chamber spaced from the walls thereof and having openings establishing communication with the melting chamber.

6. A device of the character described, comprising a kettle for melting lead and like metals having a separate melting chamber extending into the kettle through the top thereof, means providing communication between the melting chamber and the kettle, and a removable chamber in said melting chamber spaced from the walls thereof and having openings in proximity to its bottom establishing communication with the melting chamber.

CONRAD C. JACOBSON.
